UNITED STATES PATENT OFFICE.

WILLIAM C. FARNUM, OF ARLINGTON, VERMONT.

TYPE-WRITING MACHINE.

SPECIFICATION forming part of Letters Patent No. 570,158, dated October 27, 1896.

Application filed March 19, 1895. Serial No. 542,342. (No model.)

To all whom it may concern:

Be it known that I, WILLIAM C. FARNUM, a citizen of the United States, residing at Arlington, in the county of Bennington and State of Vermont, have invented certain new and useful Improvements in Type-Writers, of which the following is a specification.

My invention relates to that class of typewriters in which are embodied the features 10 of a traveling paper-carriage, a platen-roll mounted thereon around which the paper is carried, arranged to be swung transversely across the line of travel of the carriage, and a set of type-bars, each carrying a plurality 15 of types.

The object of my invention is to provide means for swinging the platen-roll by the operation of levers or keys forming a part of the regular keyboard of the machine into the various 20 positions required to be fairly struck by the respective types on the type-bars.

The invention is shown in the accompanying drawings, of which—

Figure 1 is a plan view showing the carriage 25 and the parts which coöperate to swing it at rest or in their normal position. Fig. 2 is a plan view of a portion of the platen-roll in the most elevated of its several possible positions, together with the arm by which it is 30 swung. Fig. 3 is a plan view of a portion of the platen-roll in an intermediate position, together with the arm and lever by which it is swung. Fig. 4 is a side elevation of the machine. Fig. 5 is an end view of the carriage, the swinging arm and platen-roll being in the same positions as in Fig. 2. Fig. 6 is a partial elevation of the opposite end of the carriage, with the platen-roll in the same 35 position as shown in Fig. 1. Fig. 7 is an elevation of the same end of the carriage as is shown in Fig. 6, with the platen-roll in the position shown in Fig. 3.

In the drawings the traveling carriage is shown at S, to two upright arms of which the platen-frame I is hung by means of the 40 hangers K. The frame I is also partially carried by a pair of rolls X and Y, running on suitable tracks S' and S" on the carriage-frame S. The method of supporting the platen-roll is 45 optional, however, and does not form a part of this invention, which pertains simply to

the means for shifting and lifting the said platen-roll and its frame.

In Figs. 1 and 4 W is the main frame of the type-writer. B is a rocking shaft with bearings at each end in the frame W, and A A are two arms attached to the shaft, as shown, and forming at their outer ends keys which are located on opposite sides of the machine adjacent to the regular type-keyboard. Fixed 55 to the shaft B, between its bearings, is an arm C, with the bar or link D, hinged thereto by the pin c. The link D is connected at its opposite end, by the pin d, to an arm E of the upright shaft H, which shaft is supported by 60 two bearings in the frame W. The shaft H is bent at its upper end to a horizontal position and into the form of an L, as shown, with the foot of the L depressed, thus forming at its end a downwardly-projecting finger. 65 (Shown more clearly in Figs. 6 and 7.)

Mounted upon the top plate of the frame W is a stud P, which forms a pivot for a shift-block N, consisting of an upright hub having the projecting cap-plate n and shift-hook J. 75 A roller O is carried between the plate n and hook J, against which the back edge of the platen-frame I bears under pressure of a spring in the roller-hanging mechanism provided for the purpose. The top plate n projects over the frame I, Fig. 1, and serves as a guide for the same. A stud Q forms a stop for the shift-block, against which the plate n and hook J strike when forced back by the swinging platen-frame I. The shifting hook 80 J projects outwardly and is adapted to be 85 acted upon by the back of the finger h.

In Figs. 6 and 7 is shown a type-bar T^a in position against the platen-roll. This type-bar carries a lower-case letter t' and an upper-case letter t''. In Fig. 6 is shown the position of the platen-roll when printing lower-case letters, which position of parts corresponds to that shown in the plan view, Fig. 1. This is the normal working position of 95 the machine.

Pivoted to the lower end of the shaft H is a plate F, carrying a finger-knob f, to the lower end of which beneath the plate the end of a coiled spring G is attached by means of 100 a screw g, the other end of said spring being attached to a leg of the frame W, Fig. 4.

Normally this spring and plate stand as in Fig. 1, with the upwardly-projecting lug U pressing against the arm E.

Fig. 7 shows the platen-roll in position for printing upper-case letters and corresponds to that shown in the plan view, Fig. 3. The change of shift from lower to upper case letters is accomplished by depressing the key-arm A, which, through the connecting-link D, swings the arm E, and by it the shaft and arm H, into the position shown in Fig. 3. The back of the finger h on the end of the arm H presses during this movement against the shift-hook J, causing the same to swing around against the stud Q, thereby swinging the roller O, and with it the platen-roll, into the position shown in Figs. 3 and 7. The removal of the pressure applied to the key A allows the spring G to return the parts to their normal or lower-case position.

The platen-roll may be swung into or held in the upper-case position independently of the key depression by swinging the plate F by means of knob f around until the lug U strikes the arm E, as in dotted lines, Fig. 3, when the tension of the spring G becomes effective to prevent the return of the arm H and roll L to their normal positions.

The shift-block N is located so that the roller O will bear against the traveling platen-frame I directly opposite the printing-point of the type. This is to insure correct alignment of the printed letters, as any slight oscillation of the paper-roll, due to looseness or play existing in or between the movable carriage and frame of the machine, will, from the constant pressure of the platen-frame I against the roller O, take place about the roller O as a fulcrum, and practically will be nullified at the printing-point owing to its close proximity to the fulcrum or roller O.

In Fig. 5 the platen-roll L and its frame I are shown elevated, so that the portion of the platen-roll which has been underneath receiving the type-impressions is thrown up into view of the operator. The roll thus elevated is shown in dotted lines in Fig. 4. This elevation of the platen-roll may be accomplished by the hand directly applied to any portion of the roll itself, or more conveniently by lifting one of the keys A A, as shown in dotted lines, Fig. 4, thus swinging the arm C and the connecting-link D, as shown.

The position assumed by the plate F, Fig. 1, and the arm H with the hook h when the keys A A are thus elevated, is shown in Fig. 2. In this movement the front or top face of the hook h impinges against the back bar of the platen-frame I and pushes the same forward, tilting it into the position shown in Fig. 5. The removal of the lifting force applied to the key A allows the platen-roll to fall to its former position before lifting. This elevation of the platen-roll may be performed when the shifting arm F is in the dotted position shown in Fig. 3. In this case the parts will pass,

during the swing of the arm H, in the direction indicated by the arrow, Fig. 3, through the normal position in Figs. 1 and 4 to the elevated one of Figs. 2 and 5.

70

Having thus described my apparatus, I claim as my invention, and desire to secure by Letters Patent, the following:

1. In a type-writer the combination with a traveling and swinging paper-roll frame, of an oscillating shift-block adapted to be operated from the keyboard, and carrying a roller in contact with the traveling paper-roll frame, and a vertical shaft which is interposed between the keyboard and the shifting-block and provided with a rigid horizontally-bent hooked end for engaging the said shifting-block substantially as specified.

2. The combination with a traveling and swinging platen-carriage of an oscillating shift-block a coöperating arm a shaft with which it is rigid and means connected therewith for swinging it about a perpendicular axis whereby said block may be operated by the depression of one of the keys, substantially as specified.

3. The transversely-movable paper-holder of a type-writer and a pivoted shift-block arranged to shift the position of said holder, in combination with an arm having a downwardly and rearwardly inclined finger, arranged to move the said shift-block when the said finger is depressed a rock-shaft carrying the said arm, and one or more keys and intervening devices for rocking the said shaft and thereby depressing the said arm and finger, substantially as set forth.

4. The combination of a rock-shaft with a swinging arm, a key-shaft, direct crank connections between the said rock-shaft and the said key-shaft, and one or more keys attached to said key-shaft so arranged that the lifting of said keys will cause the said swinging arm to move forwardly and raise the paper-holder, and the depression of said keys will cause the said swinging arm to move backwardly and operate a carriage shift-block, substantially as specified.

5. In combination with a movable platen-roll, a pivoted shifting-block provided with a roll arranged to bear against an attachment of said platen-roll, said block having also a projecting hook J, an arm H, bent into hook form and provided with a terminal finger h, and means for rocking the said arm about an axis so as to make the said finger engage and operate the said hook, thereby moving the said platen-roll in order that it may be in position for the printing of the upper or the lower case of type substantially as set forth.

In testimony whereof I have hereto subscribed my name this 16th day of March, 1895.

WILLIAM C. FARNUM.

In presence of—

FRANKLIN SCOTT,
EMILY SCOTT.
